UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

ADJUSTABLE JACK

Application filed July 20, 1928. Serial No. 294,092.

This invention relates to adjustable jacks and more particularly pertains to an adjustable roof jack especially adapted to use in mines.

5 An object of this invention is to provide an improved adjustable jack. Another object is to provide an improved mining jack which is of exceedingly simple and rugged construction and which may be set up and 10 taken down quickly and with facility. These and other objects and advantages of this invention will, however, subsequently more fully appear.

In the accompanying drawing there is 15 shown for purposes of illustration one form which the invention may assume in practice.

In this drawing,—

Fig. 1 is a longitudinally extending sectional view, partially in elevation, illustrating one form of the improved jack.

Fig. 2 is a transverse sectional view taken on line 2—2 of Fig. 1.

Fig. 3 is a fragmentary view taken on the same plane as Fig. 1 and showing the parts 25 in a different position.

Fig. 4 is a perspective view illustrating a part of the improved adjusting means.

Fig. 5 is an elevational view illustrating the jack set up in operative position in a 30 mine.

In this illustrative embodiment of the invention there is shown an adjustable mine jack generally designated 1 having improved adjusting means 2. The improved jack comprises a main tubular body 3 having suitably fixed thereto at its upper end a member 4. Pivottally connected at 5 to the member 4 is an adjustable abutment or support engaging member 6 having serrations on its upper surface 35 adapted to engage suitable blocking or the mine roof. As shown fixed as by rivets or other suitable attaching means adjacent the lower end of the tubular jack body 3 is a flanged collar or coupling member 7 having formed thereon a semi-circular guideway 8. Rotatably mounted in the guideway 8 is an annular flange 9 herein formed integral with a rotatable housing or casing member 10.

The improved adjusting means for the jack 50 herein comprises an adjusting nut 11 thread-

edly connected by right hand threads as at 12 within a bore formed within a boss 13 projecting laterally from the housing 10. As shown this adjusting nut 11 has pivotally connected thereto at 14 a handle member 15. The nut 11 is in turn threadedly connected at 16 by left hand threads to a nut member 17 slidably mounted within a chamber or lateral recess 18 formed within the housing. As shown in Fig. 2 the nut member 17 is held against rotative movement by means of a pin 19 secured within the housing and projecting at its inner end within a groove or slot 20 formed in the side of the nut member. This nut member 17 has formed thereon on its inner surface teeth 21 which are engageable with the helical teeth of an axially movable adjusting screw 22. This adjusting screw extends through a central opening 23 in the housing and is telescopically arranged within the tubular jack body 3. This screw is provided at its outer or lower end with an abutment engaging member or foot piece 24 having spaced points 25 for maintaining the adjusting screw against rotative movement during adjustment of the jack. This foot piece is engageable with suitable blocking or the mine floor. Arranged diametrically opposite from the handle member 15 and pivotally mounted at 26 on the housing 10 is a handle member 27 similar to the handle member 15.

In the use of the improved adjustable jack the operator first places the jack in the position shown in Fig. 5 and then grasps the handle 15, which is at that time in the dotted line position shown in Fig. 1, and rotates the adjusting nut 11 thereby moving the nut 17 axially into its released position out of engagement with the adjusting screw as shown in Fig. 3 thereby permitting the adjusting screw to slide freely downwardly until the foot piece 24 engages the blocking or the mine floor. The operator then again rotates the adjusting nut 11 thereby moving the nut 17 axially inwardly into engagement with the adjusting screw as shown in Fig. 1, the teeth on the nut 17 meshing with the teeth on the adjusting screw at that time. It will be noted that the right and left hand threads

100

12 and 16 respectively will give the effect of a double screw, making it necessary to rotate the handle only a very small amount in order to move the nut 17 the desired distance. The operator then swings the handle member 15 and 27 from the dotted line positions shown in Fig. 1 to the full line positions and then bodily rotates the housing 10 relative to the tubular jack body thereby causing the nut 17 to feed the adjusting screw 22 outwardly thereby forcing the adjusting screw and tubular jack body apart and as a result the jack is rigidly held in position. The nut 17 prevents separation between the adjusting screw and the jack body when the jack is so positioned. When it is desired to take down the jack the operator merely rotates the housing 10 relative to the jack body thereby loosening the jack parts and thereafter releasing the nut 17 from engagement with the adjusting screw permitting the latter to be slid freely inwardly within the jack body. The adjusting screw may be held in its inner or retracted position by the nut 17.

As a result of my invention it will be noted that an improved adjustable jack is provided which is composed of a relatively few parts of simple yet rugged construction especially adapted to withstand the severe usage encountered and which may be adjusted expeditiously and with facility. Furthermore it will be noted that due to the exceedingly simple construction of the jack it may be manufactured at a minimum of expense. These and other uses and advantages of my invention will be clearly apparent to those skilled in this art.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. An adjustable jack comprising a tubular body, an adjusting screw telescopically arranged therein, and means for effecting adjustment of said screw relative to said body comprising a housing member rotatably mounted on said body and having a lateral recess, a nut slidably mounted in said recess and engageable with said screw, means for adjusting said nut into and out of engagement with said screw, and means for rotating said body, said body and screw being capable of free telescopic movement when said nut is out of engagement with said screw.

2. An adjustable jack comprising a tubular body, an adjusting screw telescopically arranged therein, and means for effecting adjustment of said screw relative to said body

comprising a housing member rotatably mounted on said body and having a lateral recess, a nut slidably mounted in said recess, threaded means for adjusting said nut into and out of engagement with said screw, and means for rotating said body, said housing member and screw being capable of free telescopic movement when said nut is out of engagement with said screw.

3. An adjustable jack comprising a tubular body, an adjusting screw telescopically arranged therein, and means for effecting adjustment of said screw relative to said body comprising a housing member rotatably mounted on said body and having a lateral recess, a nut slidably mounted in said recess, threaded means for adjusting said nut into and out of engagement with said screw, and means for rotating said body including a handle pivotally connected to said threaded means.

4. An adjustable jack comprising a tubular body, an adjusting screw telescopically arranged therein, and means for effecting adjustment of said screw relative to said body comprising a housing member rotatably mounted on said body and having a lateral recess, a nut slidably mounted in said recess, threaded means for adjusting said nut into and out of engagement with said screw, and means including a common handle for rotating said housing and adjusting said threaded means.

5. An adjustable jack comprising a tubular body, an adjusting screw telescopically arranged therein, a flanged collar fixed to said body and having a guideway, a housing member rotatably mounted in said guideway and having a radial recess, a nut slidably mounted in said recess, means connected to said housing member for adjusting said nut into and out of engagement with said screw, and means for rotating said housing member, said body and screw being capable of free telescopic movement when said nut is out of engagement with said screw.

6. An adjustable jack comprising a tubular body, an adjusting screw telescopically arranged therein, a flanged collar fixed to said body and having a guideway, a housing member rotatably mounted in said guideway and having a radial recess, a nut slidably mounted in said recess, means connected to said housing member for adjusting said nut into and out of engagement with said screw, and means for rotating said housing member, said nut adjusting means and said housing rotating means including a common handle member.

7. An adjustable jack comprising a body member, an adjusting screw adapted to be telescopically received in said member, a second member rotatably carried by said body member and having a lateral recess there-in, a nut slidably received in said recess com-

prising an arcuate threaded segment adapted to engage the threads on said screw, means for adjusting said nut into and out of engagement with said screw comprising a handle carrying member having a threaded connection with said recess, and means for connecting said handle carrying member to said nut.

8. An adjustable jack comprising a body member, an adjusting screw adapted to be telescopically received in said member, a second member rotatably carried by said body member and having a lateral recess therein, a nut slidably received in said recess comprising an arcuate threaded segment adapted to engage the thread on said screw, means for adjusting said nut into and out of engagement with said screw comprising a handle carrying member having a threaded connection with said recess, and means for connecting said handle carrying member to said nut, said last mentioned means comprising a threaded connection between said handle carrying member and said nut, one of said threaded connections having left hand threads and the other right hand threads.

In testimony whereof I affix my signature.
MORRIS P. HOLMES.
